UNITED STATES PATENT OFFICE.

WALTER SCOTT, OF PLAINFIELD, NEW JERSEY.

PRINTING-MACHINE.

SPECIFICATION forming part of Letters Patent No. 312,022, dated February 10, 1885.

Application filed November 20, 1883. (No model.)

To all whom it may concern:

Be it known that I, WALTER SCOTT, of Plainfield, in the county of Union and State of New Jersey, have invented an Improvement in 5 Printing-Machines, of which the following is a specification.

This invention relates to that class of printing-presses in which the paper is supplied from a web or roll and cut off into sheets, being 10 carried through the press by tapes or belts and printed upon both sides, and delivered either to a folder or in any other convenient manner.

In my improvement the sheet is received by 15 nippers upon an impression-cylinder and conveyed to the printing-cylinder, where it receives an impression upon one side, after which the sheet is delivered directly to the second impression-cylinder, and by it presented to the second printing-cylinders for printing 20 the opposite side of the sheet, after which such sheet is taken away either by belts, or preferably by a delivery-cylinder and nippers, which pass such sheet off between belts to the folder or other place of delivery. In this mode of 25 printing it is necessary to perforate the paper at the place where one sheet is to be separated from the other, and the belts which convey the paper into the printing-press and the nipping-rollers are so arranged and speeded that 30 the advancing end of the web of paper is seized and the sheet pulled off by the accelerated motion, separation taking place upon the line of the punctures or perforations. The accelerated motion is sufficient for the impression- 35 cylinder to make two revolutions to each sheet that is received, so that such impression-cylinder carries around the sheet and holds it while being imprinted by the types. It then passes around and delivers the sheet to the 40 next impression cylinder, and upon the second rotation grasps the advancing end of the next sheet, and the operation is repeated.

In the drawings, Figure 1 is a vertical longitudinal section of the printing-press. Fig. 45 2 is a diagram illustrating the details of the gearing, cams, &c. Fig. 3 is a side view of one of the cams, and Fig. 4 represents the axis and knuckle of the gripper.

I make use of two form-cylinders, A and A', 50 the shafts of which are supported in suitable bearings in the frames A³. Each of these form-

cylinders is provided with the necessary clamps for the reception of types, stereotype-plates, or other printing devices—usually for the reception of the frame or turtle carrying the 55 type. The types occupy from about one-third to nearly one-half of the circumference of the cylinder, the remainder being a plain inking-surface. Beneath these form-cylinders are the impression-cylinders B and B', each one being 60 of half the diameter of either printing-cylinder. It is preferable to connect the shafts b⁵ and b⁶ by gear-wheels, as indicated by the dotted lines in Fig. 2, and to connect these gear-wheels, 65 respectively, to gear-wheels upon the shafts a⁵ a⁶ of the respective form-cylinders A and A'. The power to rotate these shafts and gear-wheels may be applied to either of the shafts in any convenient manner. Upon each of the impression-cylinders B and B' there is a gripper. 70 These grippers are made in any ordinary manner; but I prefer and use a shaft carried by the cylinder, having upon it the gripping-fingers, and near one end of such shaft is a knuckle having prismatic faces or notches, 75 and against which the end of the spring u presses, as indicated in Fig. 4, so that such spring will hold the gripper either open or closed. This construction of the gripper is 80 well known.

At the end of the gripper-shaft is a crank-arm, which, coming into contact with either of the cams hereinafter described, either opens or closes the gripper. The delivery-cylinder C is of the same size as the cylinder B, and connected to the same by a gear to the gear-wheels upon the shaft b⁵, so that the said delivery-cylinder C and impression-cylinder B' rotate together, and this delivery-cylinder C is provided with a gripper, b⁴, constructed as before 85 described. The shafts b⁵ b⁶ are preferably mounted in journal-boxes or bearings that are adjustable in the frames A³, in order that the impression-cylinders may bear with more or less force against the printing-surfaces a and 95 a', respectively, of the form-cylinders A A'. Upon the shaft a⁶ of the form-cylinder A is an eccentric or cam, j, the rod of which is connected to the lever J, pivoted at 3 to the frame A³. This lever is provided with cams 4 and 5, 100 which are properly shaped to act against the crank-arms of the grippers b² b³ upon the im-

pression-cylinders B B'. The parts are placed and timed in such a manner that when the crank end of the gripper b^2 passes between the cams 4 and 5, such gripper being closed to carry the sheet to the printing operation, the cam 4 is out of the way and allows the gripper b^2 to pass by without being opened. When the gripper passes by the second time, the cam j has moved the lever J in such a manner that its cam 4 is in the path of the crank end of the gripper, and opens such gripper at the same instant that cam 5 causes the gripper b^3 of the impression-cylinder B' to close and grasp the advancing end of the sheet, which at this time has been printed upon one side, and thereby transfer the sheet from the impression-cylinder B to the impression-cylinder B'.

I make use of a stationary cam, I, upon the frame A³, which acts to close the gripper b^2 and cause the same to grasp the advancing end of the sheet as it is delivered from the belts e and e' , as hereinafter described.

It will now be understood that the gripper b^2 remains open from the time it has been opened by the cam 4 until it passes around to the cam I and closes upon the advancing end of the second sheet, and that said gripper b^2 remains closed during the whole of one revolution and until it is opened by the cam 4 upon its second revolution and the sheet delivered as aforesaid.

The counter-shaft N is driven by bevel gear-wheels R and R' from the shaft a^5 , and upon this counter-shaft N is an eccentric or cam, k, the rod of which connects with the bent lever k^3 , and this gives motion to the cam-lever K, pivoted at 8 upon the frame A³, and upon this lever K are the cams 9 and 10. The parts are shaped and the motions timed in such a manner that the cam 9 opens the gripper b^3 at the proper time for delivery of the sheet from the impression-cylinder B' to the delivery-cylinder C at the same instant the cam 10 on such lever K closes the gripper b^4 , causing the same to seize the advancing end of the sheet, which has now been printed upon both sides. The cam L is stationary, and acts to open the grippers b^4 as the sheet is taken off by the belts next described.

The belt c' passes around the delivery-cylinder C, beneath the roller 12, over the roller 13, and over the roller 14, and the belt c passes around the roller 16 and over the rollers 14 15. The printed sheet passes in between these belts c and c' , and is conveyed away to any suitable folding apparatus or delivered in any desired manner. The roll of paper F is supported by a suitable shaft or spindle in bearings upon the frames A³, and the paper passes from such roll over the feed-roller E' and down between the same and the roller E. There are springs that act upon the journal-boxes of the roller E' to cause the said roller E' to press 65 against the paper and grip the same against the roller E.

The cutting-cylinders D and D' are geared

together and to the feed-rollers E and E', as indicated by the dotted lines, Fig. 2. The cylinder D receives motion from the counter-shaft 70 N and beveled gear-wheels R² and R³. Upon the cylinder D' is a knife or cutter of any suitable character. Usually this is formed of a range of projecting lance-shaped points that pass into the paper, perforating the same, but 75 not entirely separating it, there being in the cylinder D a groove or recess, into which the points of the knife pass.

The feed-belts e are passed around the rollers f' and f^3 , and the same are tightened by 80 roller f^6 . The feed-belts e' are passed around the rollers f , f^2 , and f^4 and beneath the tightener e^5 . The rollers f and f' are adjacent to each other, and the distance between them and the cutting-cylinders D and D' is greater than 85 the length of the sheet that is to be printed upon.

The surface-speed of the cutting-rollers D D' is about one-half of the surface-speed of the rollers $f f'$; hence, when the advancing end of 90 the sheet of paper reaches the rollers f and f' , it is gripped by the tapes $e e'$ and its speed accelerated, so that the back end of the sheet is separated from the web at the line of perforation or puncture, and the advancing end of the 95 sheet is carried down beneath the guards or fingers 20, and the parts are timed in such a manner that the said advancing end of the sheet is grasped by the grippers b^2 , and said grippers b^2 move at the same speed as the rollers $f f'$ and belts e and e' ; hence the paper is passed to the impression-cylinder B' in a proper manner, and by it the said paper is carried around and receives one impression from the types a upon the form-cylinder A, as aforesaid. 105

I will now describe the apparatus for supplying and distributing the ink. Above these cylinders A and A' is the ink-distributing cylinder G, and over this are the ink-working rollers g , which are by preference of the ordinary yielding composition. The roller g' is by preference an iron roller, and the composition rollers h' and h^2 , called the "doctor-rollers," intervene between the ink-tables b and b' , respectively, of the cylinders A A' and the ink-distributing cylinder G and roller g' , and to these doctor-rollers h' and h^2 lateral movement is given at the proper time by levers h^5 and h^6 , acted upon by the cams P and P' on the counter-shaft N. 110 115 120

The parts are constructed and timed in such a manner that the doctor-roller h' is in contact with the ink-distributing cylinder G while the types a are passing adjacent thereto, after which the cam P moves the said doctor-roller 125 sidewise and brings it into contact with the ink-distributing surface b' of the cylinder A, and said cam P moves this doctor-roller h' away from the surface b before the types a reach the said doctor-roller h' . So, also, the doctor-roller h^2 is moved into contact with the ink-distributing surface b' during the proper portion of the revolution of the cylinder A, and it is moved into contact with the roller g' 130 135

during the time that the types a' are passing by the said roller h^2 .

It is preferable to communicate to the ink-distributing cylinder G an endwise movement to more perfectly distribute the ink. For this purpose I employ a rock-shaft, o , with the crank-arm o^2 acting upon a collar upon the shaft o^5 of the cylinder G , and upon this rock-shaft o is a second crank-arm, o^3 , acted upon by the grooved cam M , (see Fig. 3,) the groove in said cam being at an inclination, so as to communicate through the rock-shaft o and arms o^2 and o^3 an endwise movement to the shaft o^5 . The ink-fountain H is provided with a fountain-roller, H' , and this fountain-roller is moved progressively by a ratchet-lever and rod, i^2 , receiving motion from a cam, 33 , upon the shaft i^3 . Said cam is preferably made as part of the cam M . (See Fig. 3.) By this means the fountain-roller is rotated progressively to supply ink to the doctor-roller h , which, by means of a lever, i^6 , and cams 2 , is moved alternately into contact with the ink-distributing cylinder G and the fountain-roller H' .

The inking-rollers $s s s$ are upon frames S , supported in bearings and adapted to be moved in and out, and by the action of cams upon the shaft a^6 the rollers $s s s$ are allowed to rest upon the inking-surface b of the cylinder A , while the same is passing adjacent thereto; but these cams move the frames S outwardly, so that the inking-rollers $s s s$ may be in a proper position for the printing-surface a to pass beneath and in contact with such rollers.

The rollers $s' s' s'$ are similarly actuated—that is to say, the cams on the shaft a^5 move such rollers out into the proper position for the printing-surface a' to pass in contact with such inking-rollers, and said cams allow the inking-rollers to be in contact with the inking-surface b' while the same is traveling adjacent to such rollers. The cam M receives motion from a gear-wheel upon the shaft a^6 , acting upon a gear-wheel upon the shaft i^3 , as indicated by the dotted lines in Fig. 2.

It is preferable to make use of adjustable boxes for the shaft of the cutting-cylinder D' , in order that the same may be raised or lowered to accommodate cutting-cylinders D and D' of different diameters, and these cutting-cylinders become the measure of the length of the paper supplied into the press; hence different sizes of sheets can be printed in the same press by simply changing the sizes of the cutting-cylinders D and D' . The diameter of the impression-cylinders B and B' is greater than the diameter of the cutting-cylinders D and D' ; hence there will always be room upon the said impression-cylinders B and B' for the largest size of sheet to which the press is adapted.

It will be seen that the eccentric bushings that are provided for the journals of the doctor-rollers $h h^2$ may be turned and then clamped

by a set-screw, as seen in Fig. 2, so that each doctor may be adjusted more or less closely into contact with the surface toward which such doctor-roller is pressed by its cam. By this means shrinkage in the composition roller 70 or wear on the journals or cams is compensated.

If the impression-cylinders $B B'$ were each made one-third of the diameter of the cylinder A or A' , then the grippers must be opened 75 and closed every three revolutions.

If a feed-board is used in place of the tapes $e e'$, then the sheets may be fed in by hand.

I claim as my invention as follows:

1. The combination, in a printing-press, of the cutting-cylinders D and D' , the feed-tapes e and e' , the rollers f and f' , the impression-cylinders B and B' , the grippers b^2 and b^3 , and the form-cylinders A and A' , having printing and ink-distributing surfaces, and placed side 85 by side above the impression-cylinders $B B'$, substantially as set forth.

2. The combination, with the form-cylinders A and A' , having printing and ink-distributing surfaces and placed side by side, of the impression-cylinders B and B' and their grippers below the cylinders $A A'$, the delivery-cylinder C , grippers b^4 , receiving the sheet from the cylinder B' , and the tapes e and e' , for conveying the sheet from the cylinder C , substantially as set forth.

3. The combination, with the form-cylinders $A A'$, having printing and ink-distributing surfaces, of the impression-cylinders B and B' and the grippers b^2 and b^3 , the lever J , cams 100 4 and 5 , and an eccentric, j , for actuating the grippers b^2 and b^3 every second revolution of the cylinders B and B' , substantially as set forth.

4. The combination, with the cylinders A and A' , having printing and ink-distributing 105 surfaces, of the ink-distributing cylinder G , rollers $g g'$, around the same, the fountain-roller H' , doctor h , cam 2 , and connections from the said cam to the doctor for moving the same into contact with the ink-distributing cylinder G and fountain-roller, respectively, and the doctor-rollers $h h^2$, for transferring ink from the cylinder G and roller g' to the ink-distributing surfaces on the cylinders $A A'$, respectively, and the inking-rollers s and s' , substantially as and for the purposes set forth.

5. The form-cylinders $A A'$, having printing and ink-distributing surfaces, and one ink-fountain and the distributing and inking rollers, in combination with two impression-cylinders and grippers for transferring the paper and printing it on both sides, substantially as specified.

Signed by me this 12th day of November, 125
A. D. 1883.

WALTER SCOTT.
